DESIGN FOR A ROADSIDE MARKER

Edward S. Evans, Grosse Pointe, Mich., assignor to Evans Products Company, Detroit, Mich., a corporation of Delaware

Application February 1, 1940, Serial No. 89,919

Term of patent 7 years

To all whom it may concern:

Be it known that I, Edward S. Evans, a citizen of the United States, residing at Grosse Pointe,
in the county of Wayne and State of Michigan,
have invented a new, original, and ornamental Design for Roadside Marker, of which the following is a specification, reference being had to the accompanying drawing, forming part thereof, in which:

Fig. 1 is a front elevational view of a roadside marker showing my new design.

Fig. 2 is a side elevational view of same, and
Fig. 3 is a top plan view of the same.

The back of the roadside marker is substantially like the front shown.

I claim:

The ornamental design for a roadside marker,
substantially as shown and described.

EDWARD S. EVANS.
